CAN LABELING MACHINE

Charles M. Hesson, Hanover, Pa., assignor to Chisholm-Ryder Company of Pennsylvania, Hanover, Pa., a corporation of Pennsylvania

Application January 19, 1953, Serial No. 332,068

14 Claims. (Cl. 216—58)

This invention relates to improvements in machines for applying labels to articles such as containers and, more particularly, cans, jars and bottles.

The present application is a continuation-in-part of application, Serial No. 162,320, filed May 5, 1950, now Patent No. 2,626,075.

In labeling machines of the type to which the present invention pertains, containers such as cans, jars or bottles are rolled along a runway through the machine. During such movement, they pass pasting and label supplying stations. The labels are quickly and automatically applied to the containers by being pasted and wrapped therearound. A stack of labels is progressively fed toward the runway for application to the containers in the manner described.

In modern machines of this type, the consumption of labels is rapid and replenishment must be made rather frequently. Auxiliary feed means are provided for purposes of feeding the remainder of a previous supply of labels to the label applying station along the runway, while the main label support is lowered for the reception of a new supply of labels. Following such replenishment, the main label support again feeds labels to said station.

If the supply of labels should become exhausted and an attendant fails to replenish the same, containers would continue to pass through the machine and be pasted but no labels would be applied thereto. This would also result in the containers causing paste to be deposited, for example, on the conventional pressing pad which normally presses the labels to the pasted containers. The pasted but unlabeled containers then usually pass to another machine such, for example, as a casing machine and, upon the casing operator noticing such unlabeled containers passing to his machine, he has to interrupt the casing operations, and the customary smooth operation of the labeling and casing operations, at best, become disrupted until labels are supplied to the labeling machine.

The pasted but unlabeled containers must be removed from the labeling and casing machines and passed again through the labeling machine, cleaning of the paste from the containers usually first being required as well as removal of the paste from the pressing pad of the labeling machine. This procedure is obviously messy and time-wasting, especially where the paste is of the thermoplastic or heat softenable type.

In previous attempts to prevent the foregoing objectionable results from occurring, various means have been resorted to such as audible signals sounding when the supply of labels neared exhaustion, or a switch in the power circuit of the labeling machine was opened to stop the machine. Audible signals are satisfactory if heard by an attendant but they are by no means fool-proof to obviate the objectionable consequences described above. Thus, the switch to stop the machine is more effective. However, the latter is undesirable in that machines of this nature have many moving parts and re-

starting the same after a stop is excessively wearing on the motor and driving members in overcoming the inertia of the many stopped machine parts.

It is the principal object of the present invention to prevent the pasted but unlabeled containers from passing through the machine when labels are nearly exhausted by providing container stopping means adjacent the entrance of the container runway, the movement of said means into container stopping position being controlled by the label feeding means.

It is another object of the invention to embody electrically controlled means in the stop actuating mechanism to render operation of the stop substantially instantaneous and especially effective in modern type labeling machines which operate at high speed.

Still another object of the invention is to provide several embodiments of stop members per se which have individual characteristics and advantages under certain conditions of use and related structure and, while each is operable to perform the objects of the invention, these embodiments are not equivalents.

One other object of the invention is to provide electric mechanism preferably including a solenoid and a suitable operating circuit arranged to move a can stop member in one direction, whereby control of said circuit may be effected at a number of different locations, remote or otherwise from the labeling machine, thereby making it possible to control the operation of the labeling machine not only from the label supplying station but also from any one of a number of other machines or various locations in a canning factory, for example.

A further object of the invention is to provide in one embodiment thereof a can stop member constructed to engage the rims of a container such as a can so as to preclude the possibility of denting the sides thereof; an additional feature of this object being that the stop member per se extends preferably parallel to the axis of the container and engages the container rims in a tangential manner.

As an adjunct of the foregoing object, the stop member preferably is positioned above the runway and moves downward in stopping direction toward the runway so as to stop a container by a somewhat wedging action.

A still further object of the invention is to provide several embodiments of can stopping mechanism which are fool-proof in operation, rugged and long lasting, relatively inexpensive to manufacture, easy to install in either newly manufactured or used labeling machines, and capable of ready and accurate adjustment to operate at predetermined, precise settings.

Details of the foregoing objects and of the invention as well as other objects thereof, are set forth in the following specification and illustrated in the accompanying drawings forming a part thereof.

In the drawings:

Fig. 1 is a side elevation of one embodiment of container labeling machine utilizing the principles of the present invention.

Fig. 2 is a side elevation of the front end of said container labeling machine.

Fig. 3 is an end elevation looking into the container entrance end of said labeling machine.

Fig. 4 is a sectional view through the front end portion of said labeling machine.

Fig. 5 is a sectional view of said machine looking at the front end of the label feeding mechanism thereof, taken on line 5—5 of Fig. 1.

Fig. 6 is a sectional view of said label feeding mechanism taken on line 6—6 of Fig. 7.

Fig. 7 is a sectional view taken through one of the frame members of the label feeding mechanism, showing parts thereof in elevation.

Fig. 8 is a detail view of the trip lever shown in Fig. 7. Fig. 9 illustrates the circuit employed in connection with said one embodiment of can stop mechanism.

Fig. 10 is a front end view, partly broken away to expose details, of another embodiment of container stop mechanism in a labeling machine similar to that illustrated in Figs. 1 through 7 and incorporating the principles of the invention.

Figs. 11 and 12 jointly comprise a side elevation, partly broken away, of the labeling machine shown in Fig. 10.

Fig. 13 is a top plan view of details of the label feeding means and stop actuating members of the embodiment of container stop mechanism shown in Figs. 10 through 12.

Referring to the drawings there is illustrated a basic labeling machine which is quite similar in construction to that disclosed and described in my U. S. Letters Patent No. 1,995,306, granted March 26, 1953 to which patent reference might be had for certain details of construction, such as the arrangement of the various drive shafts driven from a single source of power, adjustable features of the machine for accommodating cans of different sizes and other details not specifically set forth in the present drawings, and described in this specification. For other details not described hereinafter, attention is also invited to parent application, Serial No. 160,320, filed May 5, 1950 and now Patent No. 2,626,075, dated January 20, 1953.

It is also to be understood that the term "can labeling machine" as used throughout the description herein is used in the generic sense to include generally containers of the type which may be advanced by rolling along a runway in a labeling machine, such containers comprising, for example, cans, jars and bottles.

In the drawings 1 indicates a platform upon which the labeling machine is mounted, the same being provided with casters 2 permitting the machine to be readily moved from place-to-place when desired.

Projecting vertically from the platform are the hollow standards 3, 4, 5 and 6 providing the main support for the superstructure, consisting of the various elements for properly conveying the cans through the machine during labeling operations. Standards 5 and 6 are constructed in two sections so that the upper sections and associated parts carrying the conveyor mechanism may be adjusted relative to the runways or tracks to accommodate cans of different sizes, said structure to be later described.

Extending laterally from the upper end of section 5' of the standard 5, is an arm 9 supporting a depending bracket 10 provided with a bearing 11 forming a support for the outer end of a rotatable shaft 12 on which are mounted, for rotation therewith, pulleys 13. The inner end of shaft 12 is received in bearings seated in the walls of a gear box 15 and extends beyond the box to receive a beveled gear 16. Between the bearings, and secured to the shaft 12, is a gear by which the shaft 12 is rotated. Castings 18, loosely connected to the pulleys 13, and carried by the shaft 12, project forwardly and act as supports for frame members to be later described.

An electric motor 19 is provided for driving the various operating parts of the labeling machine and is slidably mounted on standard 5 so as to be adjusted or raised vertically. To the shaft of the motor 19 is secured a self-adjusting pulley of a well-known design, driving an endless belt 23. The belt 23 drives shaft 12 through the gear box 15.

Referring to Figs. 1 and 3, there is illustrated the standard 6 having the upper section 6' adjustably associated therewith. The section 6' is similar to the section 5' in that it has a depending tube secured thereto and telescopically received in the lower section of the standard. Within standard 6 is a rotatable shaft 36 having threaded connection with a nut 37 rigidly secured in the upper end of the section 6', whereby rotation of the shaft 36

will elevate or lower the upper section and the associated parts as desired. It will be noted that a filler sleeve 38 surrounds the shaft 36.

Secured to the lower end of shaft 36 is the beveled gear 39 meshing with a beveled gear 40. In order that shaft 36 and the corresponding shaft in post 5 may have like movement so as to produce the same adjustments of the sections 5' and 6', a coupling shaft 41 shown in Fig. 1 is provided to the opposite ends of which beveled gears are secured, one such gear 40 being shown in Fig. 3. On referring to Fig. 3 there is illustrated a manual means for adjusting sections 5' and 6' which includes a drive shaft 42 having at one end a beveled gear 43, meshing with the beveled gear 39 and at the other end a sprocket wheel 44 over which is trained the sprocket chain 45. The sprocket chain receives its drive through the medium of the hand crank 46, shaft 47 and sprocket wheel 48. It will be apparent that on operation of the hand crank 46, section 6' of standard 6, and the parts carried thereby, will be adjusted through the medium of the sprocket chain 45, drive shaft 42, gears 43 and 39 and the shaft 36 through its threaded connection with the nut 37 secured in the section 6', and that a like movement will be imparted to section 5' through similar mechanism therein.

Again, referring to Fig. 3, the upper section 6', of standard 6, has an arm 49 extending laterally therefrom and the end of this arm has a depending bracket 50 provided with a bearing 51 forming a support for a pivoted hollow arm 52, of a frame in which feed rolls are supported, to be later described.

A shaft 53 has one of its ends journaled in the end of bracket 50, while the other end of the shaft is received in a bearing in section 6'. Keyed to the shaft 53, for rotation therewith, are the pulleys 57. Pulleys 57 are driven by the conveyor belts 59 which in turn are driven by pulleys 13.

Referring to Fig. 1, castings 18 which are carried by shaft 12 and shown as being directed forwardly and downwardly and attached to these casings in overlapping relation are the frame plates or members 60 which are secured to the castings 18 by bolts 61. The opposite ends of the frame plates or members are likewise secured to similar castings which rotatably receive shaft 53. The frame plates or members form the supports for the spring projected pressure rollers 62 which engage the conveyor belts 59 so that the latter are held in proper position to contact and feed the cans or other containers through the machine, there being mounted on the castings suitable belt tightening rollers 63.

Suspended from the castings 18 and the frame plates 60 are the hangers 64 which support container guide rails 65, the guide rails being engaged by the container ends so that the containers are properly conveyed through the machine, and passed to the labeling station. After the cans have entered the labeling machine they pass over the runway, consisting of the track sections 66, track sections 67, directly over the labels, onto the fixing pad 68, which is in the form of an endless belt, and out of the machine onto the delivery chute 69.

Referring to Fig. 3, the hollow arms 52 and 56 are shown as mounted on the shaft 53 for swinging movement and enclose the sprocket wheels 70 which are keyed to and receive their drive from the shaft 53. At the forward end of the arms there are bearings for receiving the ends of the hollow shaft 72 on which are mounted the feed and spacer rolls 73 and 73', which rolls may be of the same or different widths. Loosely mounted on the hollow shaft 72 are the sprocket wheels 74 and 75 receiving their drive through the medium of sprocket chains 76 and 77, which chains in turn are driven by the sprocket wheels 70 keyed to the shaft 53. To the inner sides of the hollow arms 52 and 56 are secured the cover plates 78.

As a means to adjust the frame comprising the pivoted arms 52 and 56 and the guard plate 94, so that the feed

ing and spacing rolls may have proper contact with cans being fed into the machine, the upper section 6' of the standard 6 and the depending bracket 50 are provided with like constructions consisting of lugs 95 (see Figs. 2 and 3) through which extend adjusting screws 96. It will be noted in Fig. 2 that the head of screw 96 contacts a lug 97 projecting laterally from the lower edge of the pivoted arm 52 and that the end of the screw engages a lug 98 projecting laterally from the upper edge of the pivoted arm 52.

Nuts 99 are contained on the screw 96, engaging the lug 95 and on adjusting these nuts on the screw the screw will be moved and through its contact with lug 98 will adjust the frame so as to hold or adjust the feeding rolls in proper position to contact and feed a container into the machine and not fall to a point where entrance of a container is prevented.

A spring 100 surrounds each of the adjusting screws 96, having one end engaging the lug 95 and the other end contacting the head of the adjusting screw. With the spring 100 in the position shown the pivoted arms 52 and 56, as well as the feeding and spacing rolls carried thereby, will be permitted to move vertically to a limited degree.

In Figs. 2, 3 and 4, 101 indicates a cradle frame comprising the spaced brackets 102 and the cross tie rod 103. Each bracket consists of a rear vertical section 104, top section 105, bottom section 106, front section 107, central vertical section 108 and rear extension 109, the latter forming a support 110 at its extreme end for the track 66. Spanning the space between the standards 3 and 6, are the bracket-supporting rods 111 which pass through the eyes 112 forming a part of the rear vertical section 104. Extending between the rear extensions 109, and mounted in the ends thereof, is a rod 113 providing a pivotal support for the yielding spring plates 114 and the plate holders 115. The plate holders 115 are recessed at 116 to receive bow springs 117 which yieldingly support the spring plates 114, the spring plates being secured to the forward end of the plate holders by suitable screws. The forward end of the plate holders 115 rest upon a transverse rod 119 supported in the top section of the brackets 102.

Extending forwardly from the plate holders are lugs 120 upon which the rear ends of the hinged plates 121 rest. These plates 121 are secured to hinge members 122 having pivot eyes 123 surrounding the cross tie rods 103. Also supported by the cross rods 103 is the can feed platform or chute 124 having adjustably associated therewith can guides 125.

Positioned between the brackets 102, and supported by cross rods 126, is one embodiment of can stop mechanism for preventing the entrance of cans into the run-way of the machine when the supply of labels is depleted to a predetermined extent, the same comprising a pair of plates 127 apertured to receive the cross rods 126 and spaced to accommodate therebetween a segmental gear 128 pivotally mounted on a pin 129. The gear 128 is provided with groups of teeth 130 and 131, the latter teeth being engaged by a rack 132 forming a part of the movable core 133 of an electrical actuating means comprising a solenoid 134, attached to the lower ends of the plates 127. A guide 135 is employed to hold the rack 132 in engagement with the teeth 131. The teeth 130 engage and operate the rack bar 136, the upper end of which comprises a can stop member and is adapted to move vertically through the guides 137 and 138. Connected to the solenoid 134 and its movable core 133 is a spring 139 functioning to hold the rack bar 136 elevated and position the stop member comprising the upper end thereof in the path of the cans being fed to the machine. The solenoid 134 operates to move the rack bar 136 downwardly removing the upper end of the rack bar from the path of the incoming cans and functions under the control of an electric circuit to be later described.

As is clearly shown in Fig. 4, the radius of the teeth 131 is materially less than that of teeth 130 of segmental gear 128. Thus the movement of core or armature 133 of solenoid 134 is multiplied by gear 128 when transmitted to the stop member 136.

Extending upwardly from the platform 1 are the end frame members 140 and 141 of the label feeding mechanism, the upper ends of these frame members being provided with extensions 142 through which pass the adjusting screws 143. Mounted on these adjusting screws, and having threaded engagement therewith, are the longitudinally extending bars 144 which may be adjusted towards or away from one another depending upon the size of the cans being labeled. The bars 144 provide the supports for the blocks 145 and to these blocks are attached the track sections 67.

Depending from one of the bars 144 are the rear guide rods 146 acting as back stops or guides for the pack of labels, while guide rods 147 extend from the other or front bar 144. Pivotedly attached to the blocks 145 and 145', as shown in Figs. 1 and 8, are the trip levers 148 which are positioned along the side edges of, and slightly below, the top labels of a pack during normal operation, these trip levers being provided with adjustable fingers 149, held in adjusted position by set screws 150. The adjustable fingers 149 operatively engage a transverse shaft 151 having its ends set in rearwardly extending arms 152 attached to the shaft 153. Midway between the arms 152 is a bell crank lever 154 comprising plates 155 through one end of which passes the shaft 151, the other end of the bell crank lever having connected thereto as at 156 a rod 157 as shown in Fig. 1. This rod 157 operates a pawl 158 of a ratchet mechanism to be later described. Spring 158' normally holds the trip levers 148 in their elevated position due to its connection with the bell crank levers 154.

In many instances it is found that one end of a stack of labels is higher than the other due to the type of printing thereon and in order that both of the trip levers may be properly positioned relative to the labels, and both fingers of said trip levers simultaneously engage the transverse shaft 151, it is necessary to provide the adjustment set forth and suitable mechanism is provided for this purpose as described in parent application Serial No. 160,320, now Patent No. 2,626,075, and to which attention is invited for details not described herein.

A stack of labels 159 is disclosed as resting upon a pallet 160, the latter being supported upon the normal feed table T comprising the longitudinally extending transversely spaced table sections 161, 162 and 163 and extending through the table section 161, intermediate the ends thereof, are the rods 164 upon which the table sections 162 and 163 rest. The guide rods 146 and 147 are adjusted, as previously described, according to the width of the labels being used. The table construction just described is pivoted to a head block 166, formed integral with the rack bar 167, so that the table may be tilted as required to properly present the labels to a can. This adjustment of the table is accomplished by providing the table section 161 with a depending lug 168 and pivotally connecting this lug to the head block 166. The table is held in operative position by a spring 170 against an adjusting screw 169. To the rear of the guide rods 146, and attached to the end frame members 140 and 141 of the labeling mechanism, is a stop plate 171, shown in Fig. 5, for correcting positioning the pallets 160 with reference to the table T and the conveyor chains to be later described.

The means for elevating the auxiliary label supports or pallets comprises the following structure.

Journalized in like bearings 172, in the frame members 140 and 141, is a rotatable shaft 173 having keyed thereto the sprocket wheels 174, the shaft 173 having one of its ends passing through the frame 140 and keyed thereto is another sprocket wheel. Positioned forwardly of

the shaft 173 is another rotatable shaft 176 journaled at its opposite ends in like bearings, in the frame members 140 and 141, and having keyed thereto sprocket wheels 178, the shaft 176 having one of its ends passing through the frame member 140 and keyed thereto is another sprocket wheel. Also mounted in the frame members 140 and 141 are the stub shafts 180, rotatably carrying the sprocket wheels 181 and 182. Extending forwardly of the frame members 140 and 141, and attached thereto are the brackets 183 forming the support for the rotatable shaft 184, carrying the sprocket wheels 185. Trained around the sprocket wheels 174 and 181 are the sprocket chains 186 to links of which is secured a rung 187 adapted to provide a support for the inner end of a pallet 160.

Trained around sprocket wheels 178, 182 and 185 are sprocket chains 188, similar in form and function as sprocket chains 186, and to links thereof is secured a rung 189 adapted to provide a support for the outer end of a pallet 160. As the pallets are supported on the rungs 187 and 189 any movement of the chains in the direction indicated by the arrows will elevate the pallet and labels supported thereby. Sprocket chains such as 192 respectively drive sprocket gears fixed to shafts 173 and 176. These chains are driven at the same rate of speed by suitable gearing. The pallets 160 are moved vertically by the rungs 187 and 189 and retained in a horizontal plane.

Extending longitudinally of the labeling machine, and journaled in suitable bearings, is a driven shaft 196 intermittently rotated by a ratchet mechanism 239 described in detail in application Serial No. 160,320, now Pat. No. 2,626,075.

The drive shaft 196 is intermittently rotated by the ratchet mechanism 239 and, by suitable clutches 202, 203 and 220, 227, the driving force of shaft 196 may be imparted selectively to elevate either the main label table T or the auxiliary label supports or pallets 160. The ratchet drive of ratchet mechanism 239 is oscillated continuously by a continuously driven shaft 247 and associated chain and sprocket gearing 248. This driven shaft 247 is operatively connected with the driving mechanism contained within the standard 5 and in addition to providing the drive for the ratchet mechanism extends therebeyond to be operatively connected with the glue supplying mechanism 249 which functions to apply spots of glue on the cans as they pass through the machine. As the labels are removed from the top of the pack by the cans the trip levers 148 are moved downwardly by can contact and through the associated mechanism, described in detail in said Pat. No. 2,626,075, the ratchet mechanism 239 is caused to elevate the labels.

On referring to Fig. 6 there is disclosed, in dotted lines, a pallet 160' which has been raised by the rungs 187 and 189 and the conveyor chains 186 and 188 to a point where the same is ready to be removed from the machine by the operator. On rotation of the hand wheel 233, after placing the clutch element 227 in declutched position, the sprocket chains 188 and their associated rung will function to remove the pallet from between the labels and out of the machine. Should the operator neglect to remove the pallet and the label feeding mechanism continues to operate, the pallet 160' during its course of further vertical travel will engage the arm 265 of a sliding switch operating rod 266 thereby elevating this rod. The arm 265 extends at right angles to the sliding switch operating rod 266 and is in the path of movement of the pallet. The lower end of the switch operating rod is provided with a horizontal extension 267 carrying an adjustable contact screw engageable with a microswitch 268 and the solenoid 134 are placed in series in an electric circuit diagrammatically illustrated in Fig. 9 and comprising conductors 270 and 271, receiving current from the main switch box 272. When the micro-switch 268 is thrown in open position by move-

ment of the switch operating rod 266, being engaged by the pallet, the circuit to the solenoid is opened and the solenoid de-energized, permitting the spring 139 to raise the rack bar 136 and project the upper end thereof into the path of oncoming cans so as to discontinue the feed of cans into the machine. It is preferred in this embodiment of the invention to raise the rack bar 136 by spring means rather than the solenoid so as to avoid damaging the can which may happen to be directly over the rack bar when the latter is elevated.

Another embodiment of can stop mechanism is illustrated in Figs. 10 through 13. This embodiment incorporates principles of the invention which are also utilized in the embodiment of the invention shown in Figs. 1 through 9. However, due to the different specific characteristics of the several embodiments and the adaptability thereof to various types of can labeling machines, these embodiments are not equivalents of each other even though commonly embodying certain basic principles of the invention.

In the second embodiment of the invention shown in Figs. 10 through 12, an electrically controlled can stop mechanism, generally designated 300, is shown positioned adjacent the entrance of the runway consisting of track sections 66 and 67 as well as flexible plate 114 to which cans are fed from chute 124. It will be understood that the frame members 60 which support the can conveyor belts 59 are movable vertically relative to the runway so as to adapt the labeling machine to containers of different diameters. The frame members 60 and mechanism supported thereby are movable as aforesaid by the mechanism described above relative to the embodiment illustrated in Figs. 1 through 9. From Figs. 10 and 11 it will be seen that the can stop mechanism 300 which is directly attached to standard 6 and depending bracket 50, will move with the frame members 60 and the associated mechanism as the latter is adjusted vertically to different positions relative to the runway. Exemplary containers, designated as can 302 in Figs. 10 and 11, are introduced to the runway of the machine by moving along feed chute 124 preferably by gravity. The chute 124, in the preferred embodiment of the invention, is fixed relative to the runway.

The can stop mechanism 300 comprises a pair of supporting arms 304 and 316 which are respectively bolted to the depending bracket 50 and standard 6. A generally U-shaped stop member 308 comprises a stop bar 310 and arms 312 and 314 are preferably integral with the opposite ends of the stop bar 310 and extend transversely therefrom. The arms 312 are pivotally attached by pivot bolts 316, for example, to the outer ends of supporting arms 304 and 306 as clearly shown in Figs. 10 and 11.

Movement of the stop member 308 in one direction is effected by a solenoid 316 which, for convenience, may be secured by any suitable bracket to the standard 6. A suitable armature 318 depends from the solenoid 316 and the lower end thereof is pivotally connected to the free end of arm 314 of the stop member 308. If desired, separate solenoids for each of the arms 312 and 314 may be provided but it has been found that a single solenoid is satisfactory to achieve desired results, the same being pivotally connected only to the arm 314.

It has been stated that the electrical actuating means comprising solenoid 316 and armature 318 moves the stop member 308 in one direction. Said direction is preferably toward the can stopping position illustrated in Figs. 10 and 11. In Fig. 11 the position of the stop member 308, when in stopping position, is shown in full lines whereas, in dotted lines, said member is illustrated in its inoperative or non-stopping position. A suitable bracket 320 is also supported by the standard 6 and projects horizontally as shown in Fig. 11 for purposes of supporting stop member actuating means comprising

one end of a coil spring 322, the other end of which is connected to arm 314 of the stop member 308. Said spring 322 moves the stop member 308 in the opposite direction to the solenoid 316 and, in the specific illustration herein, said opposite direction is toward the inoperative or non-stopping position of the stop member 308, said position being illustrated in dotted lines in Fig. 11.

It will be noted that the stop bar 310 is shown in the nature of a flat bar or elongated plate in its full line, stopping position shown in Fig. 11. The plane of the bar 310 is disposed substantially tangentially to the circumference of the can 312 engaged by said bar when in stopping position. This type and arrangement of can stopping mechanism has a number of distinct advantages over the can stopping means commonly in use at present on can labeling machines. One advantage comprises the fact that the bar 310 is above the runway and moves downward from its inoperative position to its operative stopping position, whereby gravity aids in such movement of the bar 310 and action of the solenoid thereby is facilitated.

Further, the bar 310 extends substantially parallel to the axis of the cans while moving along the chute 124, said bar also being parallel to the plane of said chute. Inasmuch as the bar is materially longer than the normal container contemplated to be labeled by the labeling machine, portions of said bar simultaneously will engage the rims of the opposite ends of cans when engaged by the same to stop them and thus will preclude any possibility of denting the sides of the cans as is sometimes possible with conventional stop members now in use. Still further, the tangential disposition of the stop bar 310 to the circumference of a can 302, when the bar is in stopping position, will minimize any damage to even the rims of a can 302 when engaged by the stop bar 310.

As is also evident particularly from Fig. 11, the disposition of the stop bar 310 in stopping position relative to a can 302 is such that a gradual wedging action takes place upon a can being brought to rest by the stop bar. That is, the engagement of the rims or other portions of a container with the stop bar is a somewhat sliding engagement as distinguished from an abrupt impact as is now commonly the situation in conventional can stop mechanisms. An additional advantage also resides in the fact that a minimum of movement of the stop bar 310 is necessary between inoperative and operative or stopping positions. It is merely necessary normally to space the bar 310 above the relatively fixed feed chute surface 124 sufficiently to permit the passage of cans beneath the lowest edge of the stop bar 330. It is conceivable that movement of the stop bar merely a small fraction of an inch below its inoperative or non-stopping position will be adequate to effect stopping of a can, as long as such movement lowers the lowest edge of the bar 310 toward the feed chute 124 a distance less than the diameter of the container to be stopped by the bar 310.

As in the first embodiment illustrated in Figs. 1 through 9, the second embodiment illustrated in Figs. 10 through 13, is so arranged that the actuation of the stop member 308 is effected preferably by the feed of a pack of labels to the feeding station located intermediately of the ends of the runway. That is, when the supply of labels becomes exhausted to a predetermined minimum, the stop member 308 will be moved from its inoperative to its operative or stopping position shown in full lines in Fig. 11. The feed table T is moved vertically by the same mechanism as described above relative to the embodiment shown in Figs. 1 through 9. This table is more clearly illustrated in Fig. 6 but the same is also shown in Fig. 12 and is arranged to support a pallet 160.

In Fig. 12, a pallet 160, supporting the remainder of a previous supply of labels is shown elevated by auxiliary feeding means, described hereinabove relative to the first T is lowered for label replenishment by an attendant.

embodiment of the invention, while the main feed table Such replenishment normally takes place without stopping the labeling machine and the labeling function can continue uninterruptedly for an indefinite period as long as the label supply is replenished at necessary intervals. Should the supply of labels become diminished to a predetermined minimum without being replenished however and the label supporting means is utilizing pallet 160, one of the fingers of said pallet is arranged at a predetermined position in its upward movement to engage a laterally projecting finger 324 fixed to the upper end of a switch actuating member 326 as clearly shown in Figs. 10 and 12. Should the pallet 160 not be used, a second finger 327 projecting laterally from the upper end of member 326 oppositely to finger 324, and preferably at a higher level, will be engageable by transverse rod 164 to actuate switch 332 when the label supply on the main support T, for example, has been depleted to a predetermined minimum.

Supported by the frame of the labeling machine at any suitable position is a supporting plate 328 which is fixed relative to the frame of the machine. Under some circumstances, the stop plate 171 of the embodiment of the machine described in detail in Figs. 1 through 9 may be used in lieu of supporting plate 328. In either event, the supporting plate 328 has a plurality of spaced horizontal posts 330 which are fixed at one end to the plate 328 and the opposite ends thereof are provided with vertically aligned guide bearing apertures which receive actuating member 326. These bearing apertures are adequate to guide the switch actuating member 326 during operative movements thereof. Fixedly supported by plate 328 is a control switch 332 which functions similarly to switch 268 of the embodiment of Figs. 1 through 9 except that said switch is connected in the power circuit in such a manner and the contacts thereof are so arranged that, normally, the switch 332 maintains the solenoid 316 de-energized. The switch 332 is preferably of the type which operates upon relatively small movement of the contact moving member 334 thereof.

Actuation of the switch is accompanied by a generally U-shaped member 336 which is slideable relative to supporting plate 328 and opposite ends of the member 336 have adjustable actuating pins 338 carried thereby. The actuating pins 338 are arranged to engage opposite ends of the contact moving member 334 of switch 332. Fixed to the member 336 and projecting through a suitable slot in the supporting plate 328, as clearly shown in Fig. 10, is a lug 340 which is apertured to receive actuating member 326. The member 326 is adjustably secured to lug 340 by means of a suitable set screw 342. By this arrangement, the amount of remaining labels controlling the actuation of the stop mechanism may be adjusted to any suitable extent. Also, a manually actuatable switch 344 may be connected in the solenoid circuit to permit an attendant ready control from the label loading station, if desired to start or stop the machine from such position.

It will thus be seen that when the remaining labels on pallet 160 for example, becomes depleted to a predetermined minimum, the pallet will engage finger 324 at the upper end of actuating member 326 and cause actuation of switch 332 which will close the circuit to solenoid 316, thereby energizing the same and effecting movement of the stop member 308 from its inoperative dotted line position in Fig. 11 to its operative full line position shown in said figure. Such movement is instantaneous and yet engagement of the stop bar 310 with a container will be such that no damage will be sustained by the container for reasons described above and effective stopping of the feed of containers to the labeling machine will be effected.

In view of the electrical control of the can stop mechanisms illustrated and described in the several embodiments of the invention, the actuation thereof may readily be effected not only by the label feeding mechanism but

from an associated machine such as a casing machine to which a labeling machine frequently feeds labeled containers, any type of conveying mechanism elsewhere in a canning factory, any other machine in a canning factory, or any automatic or manually actuated switch placed at any desired location in a canning factory, for example. Such electrical actuation of the stopping mechanism renders said type of mechanism far more universal than presently used mechanically actuated can stop mechanisms. Further, the electrical actuation is instantaneous and therefore far more rapid than conventional mechanically operated can stop mechanisms thereby permitting closer regulation of the quantity of labels remaining in the label feeding mechanism than has heretofore been possible with mechanically operated can stop mechanisms.

The second embodiment of the present invention illustrated in Figs. 10 through 13 also utilizes advantageously a can stop mechanism disposed above the runway of a labeling machine and thereby affords numerous advantages over can stop mechanism used heretofore in that maximum prevention of damage to containers and particularly tin cans is made possible.

While the invention has been shown and illustrated in its several preferred embodiments, and has included certain details, it should be understood that the invention is not to be limited to the precise details herein illustrated and described since the same may be carried out in other ways falling within the scope of the invention as claimed.

I claim:

1. A container labeling machine comprising a frame having a runway to receive and guide containers through said machine, label feeding means in said machine including a label support movable toward said runway intermediately of the ends thereof, container advancing means operable to move containers along said runway and past said label feeding means, and power means operable to drive said label feeding means and container advancing means, in combination with container stopping mechanism mounted in said machine and comprising a stop member movable in opposite directions from a non-stopping position to a container stopping position wherein said stop member intersects the path of movement of containers along said runway, said stop member being positioned forwardly of said label feeding means, stop moving means interconnected to and operable to move said stop member in one direction, an electrically actuated means operable to move said stop member in the opposite direction, a circuit connected to said last mentioned means and arranged to be connected to a source of current, a switch in said circuit, and switch actuating means having a portion positioned adjacent said runway and interengageable by said label advancing means when the supply of labels thereon reaches a predetermined minimum quantity, said switch then being operable by said actuating means so as to cause movement of said stop into the path of incoming containers.

2. The labeling machine set forth in claim 1 further characterized by said electrically actuated means comprising a solenoid and armature operated thereby and said switch being arranged normally to energize said solenoid and maintain said stop member in retracted non-stopping position until said switch is actuated when the label supply reaches a predetermined minimum, said solenoid then becoming de-energized, and said stop moving means then being operable to move said stop member into container stopping position.

3. A container labeling machine comprising a frame having a runway to receive and guide containers through said machine, label feeding means in said machine including a label support movable toward said runway intermediately of the ends thereof, container advancing means operable to move containers along said runway and past said label feeding means, and power means operable to drive said label feeding means and container advanc-

ing means, in combination with mechanism operable to discontinue the feed of cans to the runway of said machine and comprising a switch supported by said machine, a switch operating rod movably supported by said machine and having one of its ends projecting into the path of movement of the label support so as to be operable thereby, a stop member adapted to be moved into the path of movement of containers into said machine, a spring interconnected to said stop member and operable to move it as aforesaid, a solenoid interconnected to and operable when energized to maintain said stop member retracted from said path of movement, and an electric circuit in which said switch and solenoid are connected in series, whereby upon operation of the label support beyond a predetermined limit said rod will be moved and the switch opened to de-energize the solenoid to permit said spring to move said stop member into the path of incoming containers.

4. A container labeling machine comprising a frame having a runway to receive and guide containers through said machine, label feeding means in said machine including a label support movable toward said runway intermediately of the ends thereof, container advancing means operable to move containers along said runway and past said label feeding means, and power means operable to drive said label feeding means and container advancing means, in combination with container stopping mechanism mounted in said machine and comprising a stop member movable in opposite directions from a non-stopping position to a container stopping position wherein said stop member intersects the path of movement of containers along said runway, said stop member being positioned forwardly of said label feeding means, an electric solenoid having a reciprocable armature, motion multiplying means between said armature and stop member operable to produce greater movement of said stop member than said armature, said armature and motion multiplying means being operable when said solenoid is energized to move said stop member in one direction, stop moving means operable upon said armature to move it in a direction to cause movement of said stop in an opposite direction to that effected by said solenoid, a circuit connected to said solenoid and arranged to be connected to a source of current, a switch in said circuit, and switch actuating means having a portion positioned adjacent said runway and interengageable by said label advancing means when the supply of labels thereon reaches a predetermined minimum quantity, said switch then being operable by said actuating means to actuate said solenoid and cause movement of said stop into the path of incoming containers.

5. The labeling machine set forth in claim 4 further characterized by said motion multiplying means comprising a compound segmental gear having two sets of teeth of different radii respectively engageable with racks on said stop member and armature.

6. A container labeling machine comprising a frame having a runway to receive and guide containers through said machine, label feeding means in said machine including a label support movable toward said runway intermediately of the ends thereof, container advancing means operable to move containers along said runway and past said label feeding means, and power means operable to drive said label feeding means and container advancing means, in combination with container stopping mechanism mounted in said machine and comprising a stop member movable in opposite directions from a non-stopping position to a container stopping position wherein said stop member is positioned to engage a container moving along said runway and stop movement thereof, said stop member being positioned forwardly of said label feeding means, means interconnected to and normally operable to hold said stop member in non-stopping position, an electric solenoid inter-

connected to and operable to move said stop member to its container stopping position, a circuit connected to said solenoid and arranged to be connected to a source of current, a switch in said circuit, and switch actuating means having a portion positioned adjacent said runway and interengageable by said label advancing means when the supply of labels thereon reaches a predetermined minimum quantity, said switch then being operable by said actuating means to energize said solenoid and cause movement of said stop into its container stopping position.

7. The labeling machine of claim 6 in which said stop member is positioned above said runway and moves toward said runway in moving to container stopping position.

8. The labeling machine of claim 7 in which the stopping member comprises lever means pivoted intermediately of the ends thereof, the solenoid being interconnected to one end of said lever means and the container engageable portion of said stop member is at the opposite end of said lever means and positioned to be subject to gravity in moving to stopping position, thereby facilitating the operation of said solenoid.

9. The labeling machine of claim 7 in which said stop member is U-shaped and the legs thereof are pivotally supported, the portion of said member between said legs being substantially parallel to the axis of and engageable with a container when said member is in container stopping position.

10. The labeling machine of claim 9 in which said portion of said stop member between said legs is flat and is engageable substantially tangentially with a container when positioned to stop the same.

11. In a container labeling machine, the combination of means defining a passageway past which containers move incident to passing into said machine, and a stop member supported by said machine for movement toward and from said means, said member being substantially parallel to said means and the axis of containers when moving past said means and said member when

30

40

moved toward said means being spaced therefrom less than the diameter of said containers, whereby said member stops movement of containers past said means.

5 12. A container labeling machine having a container runway, in combination with a stop member extending substantially parallel to said runway and movably supported by said machine for movement from an inoperative position above said runway toward said runway to a container stopping position spaced thereabove a distance less than the diameter of said container, said stop member being engageable with a container substantially in parallelism with the axis thereof.

15 13. The labeling machine of claim 12 in which said stop member is flat and longer than said containers, said member also being disposed substantially tangentially to the periphery of a container when positioned in stopping relationship relative thereto.

20 14. A can labeling machine having a runway for cans to roll along in combination with can stopping means supported for movement relative to said runway between can stopping and non-stopping positions and comprising a substantially straight member longer than a can to be stopped thereby, said member being positioned so as to be substantially parallel to the axes of cans rolling along said runway, whereby said member when moved into said can stopping position relative to said runway simultaneously engages the rims at the opposite ends of a can.
